UNITED STATES PATENT OFFICE

KARL E. PEILER, OF WEST HARTFORD, AND WILLIAM T. BARKER, JR., OF HARTFORD, CONNECTICUT, ASSIGNORS TO HARTFORD-EMPIRE COMPANY, OF HARTFORD, CONNECTICUT, A CORPORATION OF DELAWARE

SUCTION FEEDER

Application filed September 9, 1927. Serial No. 218,398.

Our invention relates generally to the securing of mold charges from a supply body of molten glass in a glass tank forehearth, extension or like glass container, and more particularly to the gathering of such mold charges periodically from the surface of the glass supply body by suction.

An object of the invention is the provision of a reliable, efficient and otherwise practical apparatus which is adapted to automatically effect the periodic segregation in a suitable receptacle of mold charges of symmetrical viscosity, temperature and condition, gathered by suction from the surface 15 of the body of molten glass, and to periodically discharge such mold charges from the gathering receptacle.

Another object of the invention is the provision of a method of obtaining suction gathered mold charges so that their lower ends can be variably shaped at the time of their separation from the supply of molten glass.

Other objects of the invention reside in the provision of a glass suction gathering apparatus of the character described having operating parts capable of adjustment to permit the gathering by suction of portions of molten glass from a supply body at a level 30 which can be adjusted vertically according to the level of the surface of the supply body or according to the height of the particular gathering receptacle in use at a given time; to sever the gathered portions of glass from the supply body at different distances from the gathering receptacle; to independently vary the time of application and cessation of the gathering suction in the gathering receptacle and to assure instantaneous application and cessation of suction in the gathering receptacle at the proper times; and to discharge the gathered portions of glass selectively either as an intermediate station, as into a cullet chute, or at a more distant station, as at a mold filling station.

Other objects and advantages of the invention will be apparent from the following description, when considered in conjunction with the accompanying drawings, forming a part of this application, in which:

Fig. 1 is a view, mainly in side elevation but partly in vertical section, of a forehearth of a glass melting tank equipped with a suction gathering apparatus embodying the invention, only a fragmentary portion of 55 the tank being shown,

Fig. 2 is a front elevation of the forehearth and the associated gathering apparatus,

Fig. 3 is a plan view of the structure exhibited in Fig. 2, 60

Fig. 4 is a transverse vertical section through the forehearth and through the associated gathering apparatus, parts of the latter being shown in elevation,

Fig. 5 is a fragmentary sectional elevation 65 of the mechanism for supporting and operating a gathering head carrying arm of the apparatus and certain related parts, only fragmentary portions of certain members of such mechanism being shown, 70

Fig. 6 is a view similar to Fig. 5 but taken at right angles therewith,

Fig. 7 is a plan view of the structure shown in Figs. 5 and 6,

Fig. 8 is a front elevation of the gathering 75 head,

Fig. 9 is a plan view of the gathering head,

Fig. 10 is a side elevation of the gathering head,

Fig. 11 is a plan view of the gathering 80 receptacle or cup,

Fig. 12 is a more or less diagrammatic showing, mainly in plan but partly in section, of the pneumatic operating mechanism of the apparatus together with certain associated parts, including actuating or control members therefor, and 85

Fig. 13 is a fragmentary detail view, partly in section, of a valve and certain associated parts for controlling the opening and closing 90 of the gathering receptacle.

The invention provides an apparatus having a gathering receptacle mounted for vertical movement through a gathering opening in the top of a glass container to and from 95 position to gather glass from a body of molten glass in the glass container. A pair of cooperative V-notched shear blades are provided for constricting and cutting through the connecting glass between the 100

gathering receptacle and the supply body after the receptacle has been moved upward through the gathering opening. The operation of the shear blades may be timed to 5 cut the connecting glass either during part of the rise of the receptacle or after the receptacle has reached the upper end of its vertical movement, thus permitting variation of the shape of the lower ends of the gathered 10 charges. The shear blades may be operated to close and cut through the rising connecting glass with decreasing speed, thus securing a further control of the shape of the lower ends of the gathered charges. The distance 15 from the lower end of the gathering receptacle at which the shear blades will cut through the connecting glass may be varied to vary the weight of the mold charges which may be gathered at different times by the 20 same gathering receptacle. The operating means for moving the gathering receptacle vertically can be adjusted to vary the position of such path of vertical movement and particularly to vary the lower limit of the 25 vertical movement of the gathering receptacle.

The improved apparatus also comprises means for swinging the gathering receptacle laterally after it has reached the upper end 30 of its vertical movement past an intermediate station, such as a position above a cullet chute, to a more remote station, such as a position to discharge into successively presented molds on a suitably operated mold 35 table. The gathering receptacle may be stopped at the intermediate station when desired. Suitable mechanism is provided for variably controlling the application of suction to the gathering receptacle and for opening 40 and closing the gathering receptacle at the proper times in the cycles of movements of the gathering receptacle so that molten glass will be quickly drawn into the gathering receptacle when it is in its gathering position and will be retained therein until the gathering receptacle has been stopped at the intermediate station or has reached the more remote or mold filling station. The gathered 45 charges then will be discharged from the receptacle.

The means for controlling the application of suction to the gathering receptacle is controlled and regulable independently of the movements of the supporting and operating 50 structure for the gathering receptacle and includes valves mounted directly on the gathering head and operable to instantly initiate and stop suction in the gathering receptacle as such valves are opened and closed. 55 The position of the path of horizontal swinging movement of the gathering receptacle can be varied so that the positions of the ends of the horizontal swinging strokes of the receptacle can be adjusted if required to compensate for varying conditions of service.

The operations of the different operating parts of the improved apparatus may be variably timed in respect to one another to secure suction gathered mold charges of various predetermined weights and shapes under 70 varying conditions and to deliver such mold charges at a plurality of places selectively.

The invention also contemplates the provision of a novel forehearth or container for the molten glass from which charges are to be 75 gathered together with a novel and effective means for circulating the molten glass in the container so that the gathered charges will have symmetrical viscosity, temperature 80 and condition.

An apparatus embodying the invention may be applied to a forehearth 1 or other glass conduit or container which may be aperturate to a glass melting tank 2, as partially shown in Fig. 1. The forehearth 1 is 85 made of suitable refractory material and preferably is heat insulated by suitable insulation 3, which may be confined between the forehearth walls and a suitable casing 4, as best seen in Figs. 1 and 4. The casing 4 90 may be suitably reinforced and supported and may be secured to the walls of the associated tank in any suitable known manner.

The construction of the forehearth and its connection with the associated melting tank 2 95 are such that molten glass 5 may flow from the tank under a gate 6 into the forehearth. The gate 6 depends slidably through a transverse aperture 7 in the forehearth top wall adjacent to the juncture of the forehearth 100 with the melting tank and preferably is suspended for vertical adjustment in any suitable known manner, as by the cable 8, so that the glass in the forehearth may be maintained at a desired adjustable level.

The forehearth top is offset downwardly at 9 in respect to the plane of the remainder of the forehearth top for approximately half the width of the forehearth and adjacent to the front of the forehearth to produce the external clearance space 10 for a purpose to be presently stated. This downwardly offset portion 9 of the forehearth top is provided with a gathering opening 11. The insulation 3 and the portion of the casing 4 which otherwise would extend above the downwardly offset portion of the forehearth top 110 may be omitted.

The approximately longitudinal half portion of the bottom of the forehearth at the side of the forehearth opposite to that provided with the downwardly offset top portion 9 is inclined upwardly toward its outer side edge as shown at 12 in Fig. 4. An opening 13 is formed in a side wall of the forehearth structure above the glass level and laterally of the gathering opening 11, the upper wall of the opening 13 preferably being inclined as shown in Fig. 4. This opening 13 preferably is formed partly in a removable upper 120

125

130

section 14 and partly in the stationary underlying portion of said side wall of the forehearth structure (Fig. 4). A handle member 15 may be secured to the removable section 14 of the forehearth for convenience in removing and replacing the latter. A glass circulating or stirring implement may be conveniently inserted in or removed from the forehearth when the section 14 has been removed.

The glass circulating or stirring implement preferably comprises a substantially frusto-conical head 16 completely immersed in the glass underneath the gathering opening 11 and a stem 17 extending obliquely from the glass through the opening 13 in the side wall of the forehearth (see Fig. 4). The stem 17 of the glass circulating implement may be carried by a suitable chuck or holder 18 on a shaft 19 which is journaled in suitable bearings 20 and 21, respectively, on the arm of a bracket 22 on a lateral shelf extension 23 of the forehearth casing. The shaft 19 is prevented from moving axially by a collar 24 which fits thereon between the bearings 20 and 21. The bearings 20 and 21 have removable cap sections secured to the base portions thereof by screws 25 to permit convenient assembly of the shaft 19 and its mounting.

The inner end portion of the opening 13 preferably is practically closed by the portion of the stem 17 that extends therethrough so that very little heat will escape from the forehearth through the opening 13.

The inclination of the stem 17 of the implement from the horizontal preferably is such that the upper surface of the substantially frusto-conical head 16 will be tangent to a horizontal plane and will be located relatively close to the surface of the glass in the forehearth. Rotation of the glass circulating implement in the direction indicated by the arrow in Fig. 4 thus will cause a current in the glass of the forehearth at the surface thereof from the rear portion of the forehearth underneath the gathering opening because of the adhesive contact of the upper part of the head 16 with the glass. At the same time, the contact of the lower portions of the head 16 and of the immersed portion of the stem 17 with the glass will cause sub-surface movement of glass in the forehearth laterally and rearwardly from underneath the gathering opening onto the inclined portion 12 of the forehearth bottom and against the adjacent side wall of the forehearth, whence such glass will be deflected rearwardly and laterally toward the deeper portion of the glass in the forehearth. Effective circulation of the glass in the forehearth past the gathering station underneath the gathering opening thus will be assured and stagnation of relatively cool glass in the front

part of the forehearth and of chilled glass at the gathering station is prevented.

A stack 27 communicates with the interior of the forehearth adjacent to the rear end thereof and in advance of the gate 6. The stack 27 is provided with a damper 26 which can be adjusted to permit escape of more or less heated gases and products of combustion from the forehearth as desired. The temperature within the forehearth may be further regulated by supplying heat to the forehearth by means of a burner or burners arranged to discharge into the forehearth through a suitably located opening or openings, as indicated at 28, in a wall or walls of the forehearth (see Fig. 1).

A gathering head generally indicated at 29 is carried at one end of an arm 30 which is firmly secured at 31 to the upper end portion of a vertical shaft 32, as best seen in Figs. 2 and 4. The shaft 32 extends through vertically aligned openings 33 and 34 in the top and bottom, respectively, of a substantially rectangular case 35. The case 35 is supported in any suitable known manner, as by supports 36 adjacent to the portion of the forehearth that is provided with the clearance space 10 and the gathering opening 11. The gathering head may be moved vertically above the gathering opening 11 by axial movements of the shaft 32 between the full line and dotted line positions shown in Fig. 4 and also may be swung between a position above the gathering opening and a position laterally of the forehearth for purposes to be presently described by turning the shaft 32 angularly about its axis. The shaft 32 is journaled in the opening 34 and extends slidably through a collar 36. The collar 36 is disposed in the case 35 and has its upper end portion journaled in the opening 33 and its lower end portion journaled in an opening 37 in an inwardly extending bracket arm 38 on the inner side wall of the case 35. The shaft 32 is prevented from turning in the collar 36 by a spline 39 which is carried by the shaft in engagement with a longitudinal groove in the inner wall of the collar. The collar fits between the bracket arm 38 and the top wall of the case 35 and thus is prevented from moving vertically with the shaft. The lower end portion of the shaft 32 extends into a tubular housing or cap 40 that is secured at its upper end to the bottom of the case 35 and may have its upper end portion or head formed to provide an additional bearing at 41 for the shaft 32.

The mechanism for moving the shaft 32 vertically comprises a lifting arm 42 having a fork 43 at one end arranged to straddle the shaft 32 and pivotally connected at 44 to the upper ends of a pair of links 45 which in turn are pivotally connected at their lower ends by means of the trunnions 46 to a collar 47. The collar 47 is rotatably held between

the vertically spaced flanges of a collar 48 which is secured to the shaft 32 in any suitable known manner, as clearly shown in Figs. 4 to 7 inclusive. The lifter arm 42 is pivoted at its other end on a horizontal pivot shaft 49. The shaft 49 is carried at the upper end of a bracket 50 mounted on the top of the case 35.

Motion is imparted to the arm 42 by a lever 51 which is fulcrumed intermediate its length on the pivot shaft 49 and has one end portion thereof 52 formed to overlie and extend substantially parallel with the arm 42.

A bolt 53 carried by the arm 42 extends loosely through an opening in the end portion 52 of the lever 51 with which it is connected adjustably by the nuts 54 and 54' which respectively engage the bolt 53 above and below the end portion 52 of the lever 51. The other arm of the lever 51 is pivotally connected by a rod 55 with one end of a lever 56 which is fulcrumed at its other end on a horizontal pivot element 57 in the lower part of the case 35, the rod 55 extending loosely through an aperture 58a in the top of the case 35. The lever 56 carries a cam roll 58 which bears against the working edge of a cam 59 that is disposed in the case 35 on a horizontal cam shaft 60. The cam shaft 60, which is driven as hereinafter stated, is journaled in bearings 61 and 62 in the front and rear walls, respectively, of the case 35. The ends of the cam shaft project from the case for purposes which will presently appear. The contact of the cam roll 58 with the cam 59 is below the level of the cam shaft 60 (see Fig. 4) so that the lever 56, which may be slightly bent or angular in shape, as shown, will be oscillated vertically as the cam 59 turns about the axis of the shaft 60, thereby causing a corresponding oscillation of the lever 51 and the lifter arm 42 as a unit and thus moving the carrying arm 30 with the gathering head thereon vertically. The path of vertical movement of the gathering head may be adjusted vertically by adjusting the nuts 54 and 54' to vary the distance between the end portion 52 of the lever 51 and the arm 42 and to thereby adjust the lower limit of the cam controlled vertical movement of the gathering head.

The horizontal swinging movement of the carrying arm 30 results from rocking of the shaft 32 about its axis. The rocking of the shaft 32 in one direction is effected by mechanism comprising an adjustable spring cushioned link 63 (see Fig. 4) that is connected at one end by a vertical pivot element 64 to a rocker arm 65 which is integral with the collar 36. The other end of the link 63 is connected by a horizontal pivot element 66 to the upper end of a lever 67. The lever 67 is fulcrumed at its lower end on a horizontal pivot element 68 that is supported on an upstanding bracket arm 69 on the bottom

of the case 35. The lever 67 carries a cam roll 70 which bears against the working edge of a cam 71 on the cam shaft 60. The cam roll 70 is held against the cam 71 by the action of a coil spring 78, to be presently described. The lever 67 thus will be oscillated about the horizontal pivot 68 as the cam 71 rotates and motion will be imparted through the link 63, the rocker arm 65 and the collar 36 to the shaft 32, which will be rocked about its axis.

The cam 71 is formed to actuate the lever 67 so as to cause in each cycle of rotation of the cam a horizontal swinging movement of the gathering head from the position above the gathering opening 11 shown in Fig. 2 and by the dotted lines in Fig. 4 toward a mold charging position beyond the front end of the forehearth and above a mold table 72, indicated by the dotted lines in Fig. 3.

In traveling from the full line position to the dotted line position of Fig. 3, the gathering head passes across an intermediate station which is represented by the cullet chute 73 of Fig. 3 and the gathering head may be halted at such intermediate station without stopping the cam 71 or effecting any manual adjustment of the motion transmitting means between the cam 71 and the shaft 32. This is possible because of the construction of the link 63 which is best seen in Fig. 4. The link 63 includes the slidably co-engaged telescopic sections 63a and 63b, respectively, and the compression spring 63c which is located within the section 63a around the section 63b between a head 74 on an inner end of the section 63b and an inwardly extending flange 75 on the inner end of the section 63a. The section 63a is tubular in form. Consequently, as the lever 67 is swung on its fulcrum away from the axis of the cam shaft 60 as the cam 71 rotates, the resultant pull on the section 63a of the link 63 will be communicated through the spring 63c to the section 63b of the link 63 and thence through the rocker arm 65 to the shaft 32. The shaft 32 thus will be rocked as required to swing the gathering head from a position above the gathering opening toward the mold filling position but such swinging movement of the gathering head may be stopped at the intermediate station by an obstruction or stop 76 in the path of an arm 77 extending laterally from the collar 36 at the side of the latter opposite to the rocker arm 65. In Fig. 3, the arm 77 is shown only in the position that it occupies when the carrying arm 30 is in the position shown by the full lines in the same figure. The stop 76 is shown in its projected or obstructing position. It will be understood that in order to permit swinging movements of the arm 30 between the full line and dotted line positions of Fig. 3, the stop 76 must be moved to and maintained in its retracted or non-obstructing position by 120.

mechanism which will be presently described. Otherwise, the contact of the arm 77 with the projected stop 76 would prevent the arm 30 from swinging from the full line position of Fig. 3 past a position over the cullet chute 73. The further cam-actuated outward swinging movement of the lever 67 after the arm 77 strikes the stop 76 will compress the spring 63c and thus elongate the link 63 without injury to the motion transmitting mechanism between the lever 67 and the shaft 32. The arm 77 is connected by the afore-mentioned coil spring 78 to an anchoring member, such as the bolt 79 that is threaded through the rear wall of the case 35. The spring 78 thus will be placed under tension as the gathering head swings laterally outward from its position over the gathering opening and therefore will return the gathering head to position over the gathering opening as soon as the contact of the cam roll 70 with the cam 71 will permit. The anchoring member 79 can be adjusted in the opening in the wall of the case 35 through which it extends to vary the tension on the spring 78 when the gathering head is over the gathering opening. A nut 80 is provided on the outer end portion of the bolt 79 to bear against the rear wall of the case 35 for locking the member 79 in position. The pivotal connections of the outer ends of the sections 63a and 63b of the link 63 with the lever 67 and the rocker arm 65, respectively, are effected through the agency of couplings 63d and 63e as clearly shown in Fig. 4. The coupling 63e comprises a pair of pivotally connected members, the inner of which is pivotally attached to the section 63b and has a stop shoulder 250 formed thereon adapted to engage with the inner end of the section 63a so as to limit the overlap of the section 63a on the section 63b. The coupling 63d likewise comprises a pair of pivotally connected members, one of which has a portion 251 threadedly engaged with the outer end portion of the section 63a. The section 63a may have a non-circular or nut portion 252 adapted to be gripped and turned by the fingers of a hand or a suitable tool so as to adjust the threaded connection between the section 63a and the coupling 63d. The effective length of the link 63 thus may be varied within limits with consequent change of position of the path of horizontal swinging movements of the gathering head 29.

The shape of the cam 71 also is such that the gathering head is permitted to remain in line with the gathering opening 11 for a substantial part of the cycle of rotation of the cam, then is swung quickly outward to the mold filling station if the position of the stop 76 will permit, then is permitted to remain at the mold filling station for part of the cycle of rotation of the cam and finally is returned quickly from the mold filling to the

position above the gathering opening during the final part of the cycle of rotation of the cam.

The stop 76 is carried on the outer end of a stem 225 projecting from a piston 226 in a cylinder 227 (see Figs. 3 and 12). The cylinder 227 is carried at one end on an apertured wall of the case 35 so that the stem 225 extends into the case 35. The stop 76 will be disposed in the path of movement of the arm 77 when the piston 226 is maintained at the inner end of the cylinder 227 and will be disposed out of the path of movement of the arm 77 when the piston 226 is maintained at the outer end of the cylinder 227. As shown in Fig. 12, pressure fluid may be supplied through the pipe 228 to the inner end of the cylinder 227 to maintain the piston 226 at the outer end of the cylinder 227 and the stop 76 in its inactive position until a three-way valve 229 in the pipe line 228 has been actuated to shut off the supply of pressure fluid to the inner end of the cylinder 227 and to release the pressure therein. A spring 230 in the outer end of the cylinder 227 then will be effective to move the piston 226 to the inner end of the cylinder 227 and to maintain the stop 76 in its active or arm obstructing position until the valve 229 has been opened.

The gathering head comprises a body 81 which is carried at the outer end of the carrying arm 30 and is provided with a vertical cylinder 82 and with a pair of oppositely extending lateral arms 83. The arms 83 are located somewhat rearwardly of the cylinder 82.

The body 81 also includes a pendant portion 84 through which a tubular member 85 extends and is connected intermediate its length with an elbow 86 (see Fig. 9). The elbow 86 is connected by a suitable coupling 87 with a flexible tubing 88 that in turn is connected with a pipe 89. The latter is adapted for connection with any suitable source of suction and is best seen in Fig. 12. The extending end portions of the tube 85 serve as pivotal supports for pairs of ears 90 and 91 on complementary substantially semi-circular attaching plates 92. The attaching plates 92 are secured by cap bolts 93 or like fastening devices to the flanged head portions 94 of similar half portions 95 of an inverted cup shaped holder for a two part inverted cup shaped gathering receptacle. The latter comprises the longitudinal half sections 96. The sections of the gathering cup preferably are made of brush carbon or like graphite composition material such as is disclosed in the co-pending application of Karl E. Peiler, filed July 5, 1927, Serial No. 203,391. Nuts 97 on the ends of the tube 85 prevent axial movement of the tube 85 relatively to the body 81. The ears 90 and 91 on the extending outer end portions of the tube 85 are provided with upturned lugs 98 which respec-

tively are located at opposite sides of the axial line of the tube 85 and are connected pivotally at their upper ends by links 99 with the opposite ends of a cross head 100 on a stem 101. The stem 101 extends from a piston 102 in the cylinder 82 through a central opening 103 in the upper head of the cylinder 82. The cross head 100 is retained in place on the stem 101 by the nut 104. The cylinder 82 is provided with ports 105 and 106 respectively located above and below the limits of travel of the piston 102 and connected with conduits 107 and 108, respectively, (see Fig. 12). Each of these conduits includes a flexible section and the respective conduits are connected with opposite ends of a control valve 109 which in turn is connected by suitable pipes 110 and 111 with a source of pressure fluid supply 112. When the piston 102 is in the lower part of the cylinder 82 as a result of the action of pressure fluid supplied to the upper part of the cylinder from the valve 109 through the conduit 107 and the port 105, the half sections of the gathering receptacle 96 will be kept closed. As shown in Fig. 13, the valve 109 may be of a usual slide valve type of construction, having a piston valve 231 pressed at one end by a compressed spring 232 to position to establish communication between the pipes 110 and 107 and provided at its opposite end with a stem 113 pivotally connected with a pivotally suspended lever 113a carrying a cam roll 114 in contact with a cam 115 on the cam shaft 60. The piston valve 231 is adapted when actuated by the cam 115 to shut off communication between the pipe 110 and the conduit 107 and to simultaneously establish communication between the supply pipe 110 and the conduit 108 and to permit exhaust of pressure fluid from the conduit 107, whereby the piston 102 will be raised in the cylinder 82 and the half sections of the gathering cup will be swung apart about the axis of the tubular member 85 from the closed position shown in Figs. 8 and 10 to position to discharge the contents thereof. As soon as the contact of the cam roll 114 with the cam 115 will permit, the valve 109 functions because of the action of the spring 232a to resume the supply of pressure fluid through the conduit 107 and to shut off flow through the conduit 108 and to permit exhaust therefrom so that the sections of the gathering receptacle will be closed.

The opposite ends of the tube 85 are connected by branch conduits 116 and 117, respectively, with upstanding valve casings 118, the connections of the branches 116 and 117 with the casings 118 being at the sides of such casings and above seats, as at 120 for downwardly opening tappet valves, as 121. The tappet valves have stems 122 extending from the tappet valve casings to positions close to and underneath the contact portions

of tappets 123 which are pivotally supported at the outer ends of the aforesaid arms 83 of the body of the gathering head on a shaft 145. Springs 124 are coiled about the stems 122 between stops 125 on the upper end portions of the stems 122 and the upper ends of the tappet valve casings and yieldingly maintain the tappet valves against their seats. The valve casings 118 are supported on upturned arms of substantially right angular tubular members 126, respectively. The members 126 have substantially horizontal arms 128 and 129, respectively, extending slidably through the heads of out-turned aligned cylinders 130, respectively, and through lateral openings 132 in the cup holder sections 95 slightly into lateral recesses 133 in the head portions of the half sections 96 of the gathering receptacle. The extremities of the members 128 are beveled to contact tightly with complementarily beveled walls at the edges of the recesses 133. Vacuum-tight joints thus will be produced between the sections 96 of the gathering receptacle and the members 128 when such members are held in place against the beveled edge portions of the recesses 133 by the action of pressure fluid admitted through the pipes 134 into the cylinders 130 outwardly of pistons 135 in such cylinders. The pistons 135 are secured firmly to the members 128 and the branch conduits 116 and 117 include flexible sections as clearly shown in Fig. 9 to permit the required axial movement of the members 128.

As shown in Fig. 12 the pipes 134 may be connected with a suitable supply conduit 233. The latter includes a flexible section 234 and may receive its pressure fluid from the aforesaid source of supply 112. The recesses 133 communicate through ducts 136 with the longitudinal suction grooves 137 which are provided in the bore of the gathering cup at the inner edges of the contacting faces of the sections thereof when such gathering cup is closed, as shown in Fig. 8. The engagement of the members 128 and 129 with the sections of the cup also aids in supporting such sections in the sections 95 of the cup holder so that upstanding beveled flanges 138 on the head portions of the cup sections 96 will be maintained firmly in contact with the beveled walls of grooves 139 in the inner surface of the head portions 94 of the cup holder. However, the principal means for holding the cup sections removably in place in the sections of the cup holder are substantially semi-circular fastening members 140. The fastening members 140 have holding screws 141 threaded through their web portions into engagement with indentations 142 in the holder sections 95 and each has inturned fingers 143 at the ends of its arms in engagement with suitable depressions 144 in the outer wall of the asso- 130

ciated cup section 96 adjacent to the side edges of the latter, whereby such cup section will be clamped firmly in place in its holder section. When the screws 141 have been loosened, the fastening members 140 may be swung downwardly and thus detached from the cup holder sections and the sections of the gathering cup then may be withdrawn from the cup holder when the supply of pressure fluid through the pipes 134 to the cylinders 130 has been discontinued and the members 128 have been moved outwardly to release the head portions of the cup sections 96. Cup sections of various lengths and internal shapes and having lower end portions of various shapes and sizes may be used interchangeably with the same cup holder.

The valves 121 normally are held closed by the springs 124. Suction in the gathering cup will take place only when the valves 121 have been forced downwardly from their seats. Such suction will be instantly applied when the valves are open and instantly stopped when the valves are closed because of the proximity of the valves to the place of application of the suction within the cup. The tappets 123 are arranged to be actuated simultaneously to open the valves 121 when the shaft 145 is rocked in one direction. The shaft 145 is journaled in aligned bores in the arms 83 and extends transversely across the arm 30 above a space that is cut away at 146 in the bottom or web of the arm 30 to afford clearance for the swinging movement of a downwardly extending rocker arm 147 on the shaft 145. The rocker arm 147 is pivotally connected by a rod 148 with a downwardly extending arm 149 of a bell crank 150.

As best seen in Fig. 5, the bell crank lever 150 is fulcrumed on a horizontal pivot member 151 at the upper end of a supporting arm 152 on the gathering head carrying arm 30. The bell crank lever 150 also includes a rearwardly extending arm 153 which is connected by a ball and socket joint 154 with the forwardly extending arm 155 of a bell crank lever 156, which is fulcrumed on a horizontal stud 157 at the upper end of a block 158. The block 158 has vertically spaced sleeve portions 159 and 160, respectively, which slidably embrace a vertical supporting and guiding rod 161. The rod 161 is journaled at its upper and lower ends in vertically aligned bearings in horizontal arms of brackets 162 and 163 respectively, carried by an upright standard 164. The latter is secured rigidly in place on the top of the case 35, all as clearly shown in Fig. 6. The bell crank 156 includes a downwardly and rearwardly extending arm 166 which is connected by a horizontal pivot element 167 with a slide block 168 having a pair of arms arranged to straddle and slidably embrace a guide rod 169. The guide rod 169 is maintained in spaced parallel relation with the guiding and supporting rod

161 by means of a pair of upper and lower cross bars 170 and 171 so that the blocks 168 and 158 and the bell crank 156 may slide vertically as a unit between the members 161 and 169, but are prevented from swinging about the axis of the member 161 independently of the member 169. The block 158 is carried by an arm 172 which is secured to the upper end portion of the shaft 32 and thus is prevented from moving vertically independently of the shaft 32. Consequently, when the shaft 32 moves vertically, the bell cranks 150 and 156 and the blocks 158 and 168, together with the arm 172 on which the block 158 is supported, and the rod 148 that connects the bell crank 150 with the tappet actuating rock shaft 145 will move vertically in accordance with the vertical movement of the shaft 32 without any relative change in the positions of these respective members. Also, the turning movement of the shaft 32 about its axis to swing the arm 30 horizontally will be accompanied by a swinging movement of the block 158 and the parts which are connected therewith about the axis of the guiding and supporting shaft 161 without any relative change in the positions of the respective pivotally connected members. However, actuation of the rod 148 to open the tappet valves 121 or to permit closing thereof will take place when the shaft 161 is rotated independently of the shaft 32. Such independent rotation of the shaft 161 will cause the member 169 to swing about the axis of the shaft 161 from the position shown in Fig. 5 toward the arm 30. The slide block 168 will move downwardly independently of the block 158 as the horizontal distance between the axial line of the fulcrum 157 of the bell crank 156 and the center of the ball joint 154 decreases. The bell crank 156 meanwhile is swung about the axis of the member 157 so as to raise the arm 153 and the ball joint 154 and thereby to cause a pull on the rod 148. This pull on the rod 148 is sufficient to rock the shaft 145 as required to actuate the tappets 123 and to thereby effect opening of the valves 121, and instantaneous application of suction through the members 128 and 129, the recesses 133, the ducts 136 and the slots 137 to the space within the gathering cup.

This rocking of the shaft 161 to effect opening of the tappet valves is caused by the contact of a peripherally adjustable cam block or dog 173 on a disk 174 with a cam roll 175 on an arm 176 that is secured to a short vertical rock shaft 177 from which motion is transmitted to the shaft 161 through a rocker arm 178 on the shaft 177, a link 179 and a rocker arm 180 on the shaft 161 (see Figs. 3, 5, 6 and 7). The cam block 173 may be adjusted around the periphery of the disk 174, which is secured on the cam shaft 60, to time the opening of the tappet valves in relation to the other cam actuated operations of the ap- 130

paratus and particularly with relation to the movements of the gathering head and the mechanism for opening and closing the sections of the gathering cup. The tappets and the operating mechanism therefor as mentioned above preferably should remain in position to hold the valves 121 open after each actuation of the tappet operating mechanism by the opening cam block 173 and against the action of the springs 124 until a second or valve closing cam block 181 on the disc 174 strikes the cam roll 175 and actuates the tappet operating mechanism as required to permit closing of the tappet valves by the springs 124. If desired, an overthrow spring 254 may be connected with the arm 178 of the cam actuated tappet valve operating mechanism as shown in Figs. 2 and 3 to assure this result. The cam block 181 also is adjustable about the periphery of the disc 174 so that the instant of cessation of the application of suction to the gathering cup may be adjusted in respect to the time of beginning of the application of such suction.

The apparatus includes a severing mechanism for cutting the glass between the suction cup and the supply body within the forehearth after the gathering cup has been filled by suction while in its gathering position substantially as shown in Fig. 4 and has been raised through the gathering opening 11. Such severing mechanism preferably comprises a pair of V-notched shear blades 182 which are carried on the shear arms 183 pivoted on the vertical pivot member 184 for closing movement above the gathering opening 11. The vertical pivot element 184 is carried by a supporting head 185 of a slide block 186 which is retained against the inner side wall 40 of the case 35 by a pair of guiding and retaining flanges or plates 187 on the case 35. The block 186 may be adjusted vertically to vary the height of the plane at which the shear blades will close. This adjustment may be effected by means of an adjusting screw 188 which threadedly engages a vertical bore 189 in the slide block 186 and is journaled in a vertical opening in a lug 190 on the adjacent side wall of the case 35, being held against axial movement by a stop collar 191 above, and a hand wheel 191a below the lug 190. The guides 187 will prevent turning movement of the block 186 about the axis of the adjusting screw 188 as the block 186 is moved vertically.

The shear arms may be actuated to open and close the shear blades at the proper times in any suitable known manner. Suitable mechanism for actuating the shear blades 60 may comprise a cylinder 192 having a piston 193 reciprocable therein and connected by a stem 194 with a cross piece 195. The latter extends between the adjacent ends of pivoted links 196 which are connected at their other ends to out-turned arms 197 on the shear carrying levers 183. Movement of the piston 193 in the cylinder 192 from the position shown in Fig. 4 toward the shear blades will cause the shears to close and cut through the glass between the charge within the gathering cup and the glass supply body in the forehearth while a return movement of the piston 193 in the cylinder 192 will cause opening of the shear blades. The reciprocation of the piston in the cylinder 192 may be effected by alternately admitting and exhausting air under pressure to the opposite ends of the cylinder 192 at times which are selected in respect to the times of the gathering operations of the cup. The application and exhaust of pressure fluid to and from the opposite ends of the shear cylinder 192 may be controlled by a slide valve of any suitable known construction, such as indicated more or less diagrammatically at 198 in Fig. 12 as having an intake 80 connected by a pipe 199 with the pressure fluid supply pipe 110 and as having delivery outlets connected by the pipes 200 and 201, respectively, to the outer and inner ends of the cylinder 192. A slidable valve actuating 85 stem 202 extends from the valve casing and is pivotally connected with the lower end of a substantially vertical pivoted arm 203a. The latter carries a cam roll 203 in contact with the peripheral edge of a cam 204 on the cam shaft 60. As shown in Fig. 2, the arm 203a is supported at its upper end on a horizontal pivot 300 which is carried by a fixed support 301. The valve within the casing 198 is urged by a spring 205 toward the cam 204, and when the cam 204 will permit, the spring 205 functions to move the valve to position to shut off communication between the supply pipe 199 and the pipe 201 leading to the inner end of the shear cylinder 192 and to establish communication between the supply pipe 199 and the pipe 200 leading to the outer end of the cylinder 192 so that the shear blades will be closed. The valve 198 of course 90 functions to permit exhaust from each pipe 200 and 201 when such pipe is out of communication with the supply pipe 199. The valve then will again be actuated by the cam 204 against the action of the spring 205 to 95 discontinue the flow of pressure fluid through the pipe 200 to the shear cylinder and to cause pressure fluid to pass through the pipe 201 to the shear cylinder. The cam 204 is shaped so that the shears close quickly once during each 100 complete cycle of rotation of the cam about the axis of the cam shaft 60, after which the shears open and remain open for the remainder of such cycle. As shown in Figs. 2 and 12, the cam 204 preferably comprises a hub disk 204a fixed to the shaft 60 and a cam disk 204b adjustably secured to the hub disk 204a, as at 232, so as to permit the cam disk to be adjusted angularly about the axis of the shaft 60. The time of closing of the shear 105

110

115

120

125

130

blades thus may be varied at will in each cycle of operations of the machine.

The pipes 200 and 201 are provided with valves 256 which can be adjusted to vary the speed at which the shear blades will cut through the glass. The cam shaft 60 may be driven by a motor 206 which is supported by any suitable support 207 adjacent to the case 35. The motor preferably has a motion 10 transmitting connection with the cam shaft 60 through a sprocket 208 on the motor drive shaft, a chain 209 between the sprocket 208 and a sprocket 210 on a second motion shaft 211, and a worm on a second motion 211 in engagement with a worm wheel 212 (see Fig. 4) on the cam shaft 60. The cam shaft 60 may carry a sprocket 213 connected by a chain 214 with a stub shaft 215. The stub shaft 215 carries a bevel gear 216 in mesh 20 with a bevel gear 217 on a shaft 218 that extends parallel with the glass circulator shaft 19. The shafts 19 and 218 are connected to rotate in synchronism by a sprocket and chain transmission mechanism such as indicated at 219 in Fig. 2. The shaft 218 is journaled in bearings on a suitable bracket or frame structure 220 secured to the forehearth casing. The shaft 215 likewise is journaled in a suitable bearing connected with the forehearth casing, and the shaft 211 preferably is journaled in suitable bearings in side walls 30 of the case 35.

The cam shaft 60 also may carry a cam 221 for tripping a valve 222 (see Figs. 3 and 35 12) for controlling the flow of operating pressure fluid from a supply pipe 223 to a delivery pipe 224 leading to operating structure of an associated glassware forming or fabricating machine (not shown), whereby the operations of the forming machine will 40 be synchronized with the cam actuated operations of the improved feeding apparatus. The valve 222 is shown only diagrammatically, since it may be of any suitable known construction, such as is well known in the art.

It is within the purview of the invention that all of the cams which are included in the hereinbefore mentioned apparatus shall be capable of being set so as to variably time 50 the operations of the parts to be actuated thereby relatively to one another as desired. The positions in which the cams are shown in Fig. 12 and in certain of the other figures of the drawings are not necessarily the positions of such cams during the operation of the machine. Certain of such cams have been specifically described and illustrated as comprising structure which permits angular adjustment thereof about the axes of their 55 supporting shaft. If desired, each of the cams may be provided with an adjusting mechanism such as is illustrated and described in the pending application of Karl E. Peiler, Serial No. 294,792, filed May 5, 60 1919, whereby such cam can be angularly ad-

justed about the axis of its shaft during the rotation of the shaft and without stopping the operation of the improved machine.

A cycle of operations of the improved apparatus may be described as being substantially as follows:

The motor 206 is started to cause turning of the cam shaft 60 and the glass circulator operating shaft 19. Assuming that the gathering head is in the dotted line position 75 of Fig. 4 at the beginning of a cycle of operations, the rotary movement of the cam shaft 60 turns the cam 59 so that the gathering head is permitted to move downward substantially to the full line position of Fig. 4 and to remain temporarily in that position, the lower end of the closed gathering receptacle then dipping slightly into the glass in the forehearth. The lower limit of the downward 80 stroke of the gathering head has been adjusted by manipulating the nuts 54 according to the glass level in the forehearth and according to the height of the particular gathering receptacle that is in use at a given time.

The cam block 173 on the disc 174 is timed 90 to cause opening of the tappet valves 121 at a predetermined time with respect to the termination of downward movement of the gathering head, which may be immediately before the gathering head reaches its lowest 95 position, at the instant the gathering head reaches its lowest position, or at any time thereafter while the gathering head is at rest in its lowest position. The opening of the tappet valves results in the instantaneous 100 application of suction to the gathering space within the closed gathering receptacle so that molten glass will be drawn from the supply body in the forehearth into the gathering receptacle until the latter is completely 105 filled. The turning of the cam 59 about its axis of rotation then will cause the gathering head with the filled gathering cup to move upward from the full line position of Fig. 4 toward the dotted line position of Fig. 4. 110

The shear cam is adjusted about the axis of rotation of the cam shaft 60 to cause severance of the connecting glass between the gathered charge and the supply body at a time which may be selected with relation to 115 the termination of upward movement of the gathering head in order to produce a desirable shape at the lower end of the gathered charge. For example, the shear blades may close while the gathering head is moving upward so that the gathered charge held by the cup will have its lower end portion tapered or "whittled" by the co-action between the closing shear blades and the upward movement of the gathering head. The 120 cocks 256 may be adjusted to cause the closing shear blades to cut through the rising glass at a decreasing speed, which will further vary the shape of the lower end of the mold charge. Or, the shear blades may be 125

timed to close after the gathering head has reached its highest positions so that the gathered charge will have a blunt lower end. The distance from the lower end of the gathering receptacle at which the shear blades sever the glass may be varied so that more or less glass depends from the gathering receptacle after severance, which will have the effect of changing the weight of the gathered charge and also will have a slight effect on the shape of the lower end portion of the charge since the central portion of the gathered charge will be hotter than the outer portion thereof and its resultant tendency to move downwardly by gravity will have increasing effectiveness as the distance of the lower end of the gathered charge from the lower end of the gathering receptacle increases.

20 After the gathering head is in the dotted line position of Fig. 4 and the charge in the gathering receptacle has been severed from the supply body, the cam 71 will function to swing the gathering head laterally toward a discharging position over a mold on the mold table. Assuming that the stop 76 is retained in its inactive or non-obstructing position by air pressure at the time of the lateral swinging movement of the gathering 25 head, the gathering head will swing across the intermediate station above the cullet chute 73 to the mold filling station and then will pause at the mold filling station. The valve closing cam block 181 is adjusted on the disc 174 with relation to the time of arrival of the gathering head at the discharging station and in synchronism with the movements of the mold table so that a mold will be disposed in a position to be filled from 30 the gathering head at the time the tappet valves are closed to release the gathered charge from the influence of suction. Also, the cam disc 115b is adjusted about the axis of rotation of the cam shaft 60 to effect opening of the gathering receptacle at a time that is related both to the arrival of the gathering head at the filling station and to the closing of the suction controlling tappet valves. The cessation of suction in the gathering 35 head and the opening of the gathering receptacle may take place simultaneously and the gathered charge will fall by gravity into the waiting mold or the suction may be cut off after the arrival of the gathering head at the mold filling station and immediately before or after the beginning of opening movement of the gathering receptacle.

40 After delivery of the gathered charge, the sections of the mold receptacle are closed and the gathering head is swung quickly from the dotted line position of Fig. 3 to the full line position of Fig. 3 and the dotted line position of Fig. 4 and a new cycle of operations is initiated.

45 In the event that the feeder should be in

operation while the associated shaping machine is inactive and it should be desired to deliver the gathered charges into the cullet chute 73 at the intermediate station, the valve 229 is closed so that the stop 76 will be maintained in position to stop the gathering head at the intermediate station above the cullet chute and in due course of time during each cycle of operations, the tappet valves will be closed and the gathering receptacle will open to discharge the gathered charge into the cullet chute. This will take place until the valve 229 has been opened to effect removal of the stop 76 from its active position to its non-obstructing position and thereafter the gathering head will swing in each cycle of operations from its position above the gathering opening past the intermediate station to the more remote mold filling station. It is obvious that the intermediate station may be above a suitable chute or transfer device for filling molds on a second mold table instead of for delivering such charges to a cullet chute so that the same feeding apparatus may be used at different times to fill molds on two different mold tables. For example, valve 229 may be closed and opened periodically by suitable cam means timed to function at appropriate times in respect to the charge gathering and discharging means so that the gathered charges will be delivered at the intermediate station and the more remote station alternately.

50 The action of the glass circulator in the glass in the forehearth will positively prevent any stagnation of chilled or relatively cool glass in the front part of the forehearth or at the gathering station so that the mold charges which will be gathered by the use of the improved gathering apparatus will be of symmetrical temperature, viscosity and condition and because of the adjustments and beneficial features which have just been pointed out in the description of the operation of the apparatus, will be of uniform and compact shape in successive cycles for the same adjustments under the same conditions without preventing regulations within limits in different cycles of the shapes of the lower ends and the weights of such mold charges.

55 We claim:

1. In glass gathering apparatus, a gathering receptacle comprising sections adapted to be opened and closed, means for operating said receptacle to move it backward and forward in cycles between a position to dip into a body of molten glass and a position for the discharge of a pre-shaped quota of glass from the receptacle, means for supplying suction to said receptacle when it is dipping into said glass, means timed to open said receptacle at a predetermined time in each of its cycle of operations, valve means for beginning and ending the application of suction to said receptacle, and valve actuating means includ-

ing a cam, a rotary shaft upon which said cam is mounted, means for shifting said cam angularly of said shaft to change the time at which the application of suction is ended, 5 means for rotating said shaft and the cam mounted thereon, and said valve actuating means comprising connections for operating the valve means to end the application of suction in said receptacle independently of the 10 forward movement of said receptacle from one position to the other.

2. In glass gathering apparatus, a gathering receptacle having an open end, said receptacle being formed in sections adapted to 15 be opened and closed, means for opening and closing said receptacle, means for periodically moving said receptacle backward and forward between a gathering position and a transferring position, a gathering pool at 20 the gathering position, means for dipping said receptacle in the gathering pool to gather a charge of glass, means including valve means for initiating a period of suction in the receptacle when it is dipped into the glass and 25 for subsequently terminating said period of suction, and valve actuating means including separate cam members mounted on a rotary shaft, means for rotating said shaft, means for shifting at least one of said cam members on said shaft to change the duration of 30 the period of suction in said receptacle, said valve actuating means also including connections for operating the valve means to relieve the suction in said receptacle independently 35 of the forward movement of the receptacle between the gathering and transfer positions.

3. In glass gathering apparatus, a receptacle having an open end, means for periodically moving said receptacle to and from position to dip at its open end into a body of molten glass, means for initiating a period of suction in the receptacle each time the receptacle dips into the glass and for subsequently terminating said period of suction, 45 and separate means for independently adjusting the times of beginning and cessation of the period of suction in the receptacle for any selected cycle of operations of the receptacle.

4. Glass gathering apparatus comprising a receptacle having an open end, means for supporting said receptacle with its open end downward for vertical movement to and from the position to dip into a supply body of 55 molten glass, a vertically swingable arm connected with the supporting means for operating said supporting means to reciprocate said receptacle vertically in successive cycles, a lever for actuating said swingable arm, and an adjustable connection between said lever and said swingable arm for adjusting said supporting means to vary the path of the reciprocations of said receptacle.

5. The combination with a forehearth having 60 a gathering opening in its top and having

a supply of molten glass therein, a carrier extending above said gathering opening and mounted to move vertically and to swing laterally, a sectional gathering receptacle depending from said carrier in position to extend through said gathering opening to the surface of the glass in the forehearth when said carrier is at the lower end of its path of vertical movement, cam means controlling the vertical movements of said carrier, periodically operated pneumatic means for opening and closing the said receptacle, a shaft carrying said cam means, means driven by said shaft for controlling the operation of said pneumatic means, means for initiating suction in said receptacle each time it dips into said glass, means for severing the connecting glass between said receptacle and the supply body after said receptacle has moved above said gathering opening, means for terminating the suction within said receptacle on each swinging movement of the receptacle laterally from said position above the gathering opening, means for operating the last-named means independently of the movement of the receptacle, and means for variably timing the instant of cessation of said suction for any selected cycle of movements of the receptacle. 70

6. The combination with a forehearth having a gathering opening in its top and having a supply of molten glass therein, a carrier extending above said gathering opening and mounted to move vertically and to swing laterally, a gathering receptacle depending from said carrier in position to extend through said gathering opening to the surface of the glass in the forehearth when said carrier is at the lower end of its path of vertical movement, cam actuated means controlling the vertical movements of said carrier, means for initiating suction in said receptacle each time it dips into said glass, means for severing the connecting glass between said receptacle and the supply body after said receptacle has moved upward to a plane above said gathering opening, means for terminating the suction within said receptacle on each swinging movement of the receptacle laterally from said position above the gathering opening, and means for stopping the lateral swing of said receptacle at different places after different gathering operations to permit gathered glass to be delivered at said different places selectively. 100

7. Glass gathering apparatus comprising a forehearth having a gathering opening at its top, a shaft mounted to slide vertically adjacent to said forehearth and to turn about its axis, a gathering receptacle, an arm supporting said gathering receptacle on said shaft for movement vertically with the shaft through said gathering opening to and from position to depend into a body of molten glass in the forehearth and swingable laterally in a plane above the gathering opening between 110 120 125 130

a position above the forehearth and a discharging position laterally of the forehearth, cam mechanism for actuating said shaft to move said receptacle vertically to and from its gathering position and to then move the receptacle laterally to and from its discharging position, means controlled independently of said receptacle supporting means for initiating suction in the receptacle each time the receptacle dips into the glass and for terminating the period of suction when the receptacle has reached its discharging station, and severing means for cutting the connecting glass between the receptacle and the supply body after each gathering operation of the receptacle.

8. In glass feeding apparatus, a forehearth having a gathering opening through which portions of glass may be gathered periodically from the surface of a supply body of molten glass in the forehearth, said forehearth having its bottom wall inclined adjacent to the gathering station, and means operating in the glass in the forehearth for moving glass of said supply body on said inclined bottom wall and at said gathering station.

9. In glass gathering apparatus, a forehearth having a portion of its top offset downwardly from one edge thereof for part of the width of the forehearth and having its bottom inclined from the opposite side of the forehearth for part of the width of the forehearth, said downwardly offset top portion of the forehearth having a gathering opening formed therein, and a rotary implement extending into the glass beneath said gathering opening for cooperating with said inclined bottom wall of the forehearth to effect circulation of the glass in the forehearth underneath said gathering opening.

10. In glass gathering apparatus, a forehearth having its bottom wall inclined from one side edge thereof for part of the width of the forehearth and having a downwardly offset portion in its top adjacent to the other side of the forehearth, said downwardly offset top portion of the forehearth having a gathering opening formed therein, said forehearth having a removable section laterally of said downwardly offset top portion of the forehearth, said removable section and the adjacent side wall of the forehearth being cooperatively formed to produce an inclined opening slightly above the glass level in the forehearth, an inclined rotary implement extending through said inclined opening into the glass in the forehearth above said inclined portion of the bottom wall, said implement terminating in a frusto-conical head submerged in the glass beneath the gathering opening, the upper surface of said frusto-conical head being substantially tangent to a horizontal plane, and means for rotating said implement to cause the upper portion of said head to advance glass forwardly at the

surface of the supply body in the forehearth underneath the gathering opening and to impel glass at a lower level rearwardly and laterally on the inclined bottom wall, the portion of the implement in contact with the glass above said inclined bottom wall acting to impel the glass rearwardly in the forehearth. 70

11. In a suction gathering apparatus, a suction head comprising a body portion, a tubular member carried by said body portion, means for connecting said tubular member with a source of suction, a holder comprising a pair of sections hinged to said tubular member and adapted to be opened and closed, a gathering receptacle comprising a pair of cooperative sections, each partially embraced by its respective holder section, flexible suction conducting means connecting the opposite ends of said tubular member with said gathering receptacle sections, and releasable means for holding said receptacle sections in place in their respective holder sections. 80

12. In glass gathering apparatus, a glass charge carrying member movable from a starting position past an intermediate delivery station to a more remote delivery station and back to said starting position, and a stop movable to and from position to prevent said carrying member from moving past 90 said intermediate delivery station.

13. In glass machinery, a member having a normal cycle of movement from a starting station past an intermediate station to a more remote station and back to said starting station, means for operating said member to effect said cycle of movement, and means normally inactive so far as affecting the movement of said member is concerned but operable at will to prevent said member from 100 moving past the intermediate station without preventing continuance of the operation of said operating means to effect the return of said member to its starting station at the proper time in its cycle of movement. 110

14. In glass gathering apparatus, a glass holding member having a normal cycle of movement when charged from a starting position to a plurality of discharge stations in series, and back to said starting position, and means for predetermining the particular discharge station at which the outward movement of said receptacle from the starting position will be stopped to permit discharge of its contents. 115

15. In glass gathering apparatus, a movable gathering head including a gathering receptacle, means for imparting a cycle of movements to said gathering head, so as to move the gathering head from a glass gathering station to a glass delivery station and back to said glass gathering station, a valve carried by said gathering head for controlling the application of suction to the gathering receptacle, means carried with said head 125

for actuating said valve, and means operatively connected to said valve actuating means but controlled independently of the movements of the gathering head for opening and closing said valve in each cycle of movements of the gathering head.

16. In glass gathering apparatus, a movable gathering head including a gathering receptacle, means for imparting a cycle of movements to said gathering head so as to move the gathering head from a glass gathering station to a glass delivery station and back to said glass gathering station, a valve carried by said gathering head for controlling the application of suction to the gathering receptacle, means carried with said head for actuating said valve, and means operatively connected to said valve actuating means but controlled independently of the movements of the gathering head for opening and closing said valve in each cycle of movements of the gathering head, said valve control means being adjustable to independently vary the times of opening and closing of said valve.

17. In glass gathering apparatus, a gathering head including a gathering receptacle, an arm carrying said gathering head and mounted to move vertically and to swing about a vertical axis, a valve carried by said head for controlling the application of suction in said receptacle, a rod carried by said arm for operating said valve, means for operating said arm to impart a cycle of movements to said gathering head so as to move the gathering head from a glass gathering station to a glass delivery station and back to said glass gathering station, and independently controlled means for operating said rod to effect opening and closing of said valve during said cycle and in timed relation to movements of the gathering head during that cycle.

18. In a suction gathering apparatus, a two part non-metallic refractory gathering receptacle, a two-part holder having its sections hingedly connected with each other and each firmly and detachably secured to the corresponding receptacle section, each of said receptacle sections having a suction passage extending between the outer and inner walls thereof, each of said holder sections having an opening extending therein between the inner and outer walls thereof in register with the outer end of the passage in the associated receptacle section, movable suction conducting means having rigid members adapted to extend through said openings of the holder sections against the walls of the adjacent ends of the suction passages in the associated receptacle sections, and pneumatic means for holding said rigid suction conducting members in suction tight contact with the walls of said suction passages.

19. In a suction gathering apparatus, a

two-part non-metallic refractory gathering receptacle, a two-part holder having its sections hingedly connected with each other and each firmly and detachably secured to the corresponding receptacle section, each of said receptacle sections having a suction passage extending between the outer and inner walls thereof, each of said holder sections having an opening extending therein between the inner and outer walls thereof in register with the outer end of the passage in the associated receptacle section, movable suction conducting means having rigid members adapted to extend through said openings of the holder sections against the walls of the adjacent ends of the suction passages in the associated receptacle sections, valves carried by said movable suction conducting members for controlling the suction therein, and means for opening and closing said valves in unison.

20. In glass gathering apparatus, a gathering head including a gathering receptacle, an arm carrying said gathering head and mounted to move vertically and swing about a vertical axis, means for swinging said arm from a glass gathering station to either of a plurality of glass delivery stations, a valve carried by said head for controlling the application of suction to said receptacle, a rod carried by said arm for operating said valve, and means controlled independently of the swinging of said arm and head for operating said rod to open and close said valve in timed relation to the movement of the gathering head, irrespective of variations in the extent of movement of said arm between the gathering and delivery station.

21. Glass gathering apparatus comprising, a receptacle having an open end, a support for said receptacle, a gathering pool, means for intermittently swinging said support and receptacle toward and away from the gathering pool, means for dipping said receptacle into the glass in the pool to gather a charge therefrom by suction, a suction conduit communicating with said receptacle, a valve in said conduit for controlling the application of suction to said receptacle, said valve being located at the outer part of said support adjacent the receptacle, whereby suction quickly is applied to the receptacle when the valve is opened, means including a moving cam for actuating said valve, and means for adjusting the valve actuating means, to vary the duration of the period of suction.

22. In glass gathering apparatus, a sectional receptacle adapted to gather charges of glass by suction, means for opening and closing said receptacle, a support for said receptacle, means for actuating said support to move said receptacle intermittently backward and forward between a body of glass in the gathering position and a position for the release of a charge of glass from said receptacle, and for dipping said receptacle

- into the body of glass at the gathering position, means for supplying suction to the receptacle, valve means for controlling the application of suction to and for relieving the suction in said receptacle, valve actuating means including separate cam members on a rotary shaft, at least one of said members being angularly adjustable on said shaft to vary the period of suction in said receptacle,
10. said valve actuating means also including means for operating the valve means independently of the movement of said receptacle from one position to the other, means for severing the connected glass in the receptacle
15. and the body of glass after a charge has been gathered, and means driven by the rotary shaft of the valve actuating means for controlling the operation of said glass severing means.
20. 23. In glass gathering apparatus according to claim 22, cam actuated means driven by the rotary shaft of said valve actuating means, for operating said support to move the receptacle backward and forward between the glass gathering and charge releasing positions.
25. 24. In glass gathering apparatus according to claim 22, pneumatic means for opening and closing said receptacle, and means driven by the rotary shaft of said valve actuating means, for periodically actuating said pneumatic means.
30. 25. In glass gathering apparatus according to claim 22, pneumatic means for periodically operating said glass severing means, and means driven by the shaft of the valve actuating means for controlling the operation of said pneumatic means.
35. Signed at Hartford, Connecticut, this 30th
40. day of August, 1927.
- KARL E. PEILER.
